(57) CLAIM

The ornamental design for a hot air balloon cork holder, as shown and described.

DESCRIPTION

FIG. 1 is a perspective view of a hot air balloon cork holder showing my new design;

FIG. 2 is a rear view thereof;

FIG. 3 is a top view thereof;

FIG. 4 is a bottom view thereof; and,

FIG. 5 is a side view.

The broken lines depict portions of the hot air balloon cork holder that form no part of the claimed design.
